UNITED STATES PATENT OFFICE

2,373,535

TOOLHOLDER

Louis B. Brown, Duquesne, Pa.

Application September 12, 1944, Serial No. 553,740

2 Claims. (Cl. 29—48)

This invention relates to a tool holder for use on lathes, one of the objects being to provide a device of this character designed to tightly grip and hold a plurality of cutting tools, there being means provided whereby each of the tools can be adjusted to any desired angle independently of the other tools in the holder, after which a single clamping means can be utilized whereby all of the held tools will be gripped simultaneously to hold them against accidental displacement while in use.

A further object is to provide simple and efficient means for locking the holder in any position to which it might be adjusted on a lathe.

A still further object is to provide a structure of this character which is simple and compact in construction, can be adjusted readily, and can be easily handled.

With the foregoing and other objects in view, which will appear as the description proceeds, the invention consists of certain novel steps in the method and certain details of construction and combinations of parts hereinafter more fully described and pointed out in the claims, it being understood that changes may be made in the method disclosed and in the construction and arrangement of parts without departing from the spirit of the invention as claimed.

In the accompanying drawings the preferred form of the invention has been shown.

In said drawings,

Figure 1 is a top plan view.

Figure 2 is a side elevation.

Figure 3 is a section on line 3—3, Figure 2.

Figure 4 is an enlarged section on line 4—4, of Figure 1.

Figure 5 is an enlarged section on line 5—5, of Figure 1.

Referring to the figures by characters of reference, 1 designates a supporting element, having a channel 2 formed with undercut or recessed walls providing side grooves 3.

Channel 2 is designed to receive an adjustable post 4, the head 5 of which is proportioned to extend into the recesses or grooves 3. That portion of the post adjacent to the support 1 is screw threaded as indicated at 6 for engagement by a plate 7 constituting a nut which, when turned in one direction relative to the post, will frictionally engage the support 1 and cause the head 5 to grip the support as shown, for example, in Figure 4. Thus the post can be securely held in any position to which it might be adjusted within the channel 2.

Removably mounted on the post 4 is a bottom

plate 8 which is of any preferred shape, although in the present instance it is square, as shown particularly in Figure 3. Each side of the plate has a rabbet 9 in the upper portion thereof and movably mounted within each rabbet is a jaw 10 in the form of an elongated bar provided, adjacent to each of its ends, with a dowel 11, anchored as at 12 in the jaw and extending downwardly through an opening 13 in the bottom plate 8.

10 This opening is counterbored as at 14 and movably mounted in the counterbore is the head 15 of the dowel 11. The two dowels carried by each jaw adjacent its ends are both loosely mounted within the openings 13 and the counterbores 14 provided therefor, so that the jaw thus is free to tilt relative to the plate 8 although held assembled therewith and substantially restrained from longitudinal movement relative thereto.

Screw threaded openings 16 are provided in the 20 plate 8 between, but adjacent to, the dowels heretofore described and in each of these openings is seated an adjusting screw 17 which can be provided with a socket whereby a suitable wrench can be used for rotating the screw for the purpose of shifting the jaw 10 engaged thereby. Obviously, by separately adjusting these screws the jaw can be positioned at any desired angle relative to the plate 8. If necessary the holder can be removed from the post 4 to afford access to 30 the adjusting screws 17.

The parts thus far described are duplicated in connection with each of the jaws 10 at the four sides of plate 8.

A top plate 18 which is similar in construction to the plate 8, is mounted on the post 4 and is disposed oppositely thereto so that the rabbets 19 in the sides thereof open downwardly toward plate 8. Each of these rabbets contains a jaw 20 similar to the jaw 10 and each of these jaws has a pair of dowels 21 anchored therein adjacent to its ends, as indicated at 22. The dowels are slidably mounted in openings 23 in the top plate 18 and these openings are counterbored as at 24 to receive the heads 25 on the dowels 21. Thus 40 these dowels serve to support the jaws 20 against separation from the top plate 18.

Screw threaded openings 26 are provided in the top plate between and adjacent to the dowels associated with each one of the jaws and in each 50 of these openings is an adjusting screw 27 which, like the screws 17, is provided with an angular socket for the reception of a suitable wrench by which the screw can be turned to press against jaw 20 and maintain it at any predetermined angle while in gripping position.

The two plates 8 and 18 are joined by tie-bolts 28 and that portion of the post 4 extending outwardly beyond the top plate 18 is screw threaded as at 29. A cap 30 is keyed on this extended portion of the post as indicated at 31 so as to rotate with the post while being free to slide relative thereto. A nut 32 engages the threaded portion of the post and by turning the same in one direction the cap 30 can be pressed tightly against the top plate 18 so that the holder can thus be clamped tightly on to the plate 7. An annular series of recesses is formed in the periphery of the cap 30 and any one of these recesses is designed to receive a spring pressed locking pin 34 slidably mounted in a bracket 35 on plate 18 and having a knob or handle 36 whereby it can readily be withdrawn from the recess 33 against the action of the spring 37 mounted on the pin and holding it normally projected toward or into the cap 30.

In practice the post 4 is adjusted to the position in which it is to be held on the supporting structure 1, after which the nut formed by plate 7 is screwed tightly against the support to hold the post in the position to which it has been moved.

The cutting tools T to be mounted in the holder are placed between the opposed jaws 10 and 20 and by means of the screws 17 and 27, these jaws are forced against the tools and are brought to the correct positions for holding the tools at proper angle relative to the plates 8 and 18. With the parts thus adjusted and assembled, the tie bolts 28 are tightened and all of the tools thus securely gripped so that they cannot shift relative to each other. The holder is then placed on the post 4 where it is secured by tightening the nut 32.

By withdrawing the pin 34 from engagement with the cap 30, the entire holder can be rotated

on post 4 so as to bring any one of the tools into working position, whereupon pin 34 is released and will snap into the adjacent recess 33, thereby securing the screw against displacement during the cutting operation.

Obviously, tools of different thicknesses and of different types can be held simultaneously within the device and any one of them quickly brought into working position, as will be readily seen.

10. What is claimed is:

1. A tool holder including a post, opposed plates mounted for rotation on the post, each plate having rabbeted edges providing seats, elongated jaws positioned for movement in the respective seats, dowels extended from each jaw and slidably and tiltably mounted in one of the plates, adjusting screws in each plate between the dowels engaging one of the jaws, the jaws on the plates being oppositely disposed and positioned to receive cutting tools therebetween, and means separate from the post for drawing the plates toward each other to simultaneously bind all of the jaws upon the interposed tools.

2. A tool holder including a post, opposed plates mounted for rotation on the post, each plate having rabbeted edges providing seats, elongated jaws positioned for movement in the respective seats, dowels extended from each jaw and slidably and tiltably mounted in one of the plates, adjusting screws in each plate between the dowels engaging one of the jaws, the jaws on the plates being oppositely disposed and positioned to receive cutting tools therebetween, and means separate from the post for drawing the plates toward each other to simultaneously bind all of the jaws upon the interposed tools, and selective means on the post and one of the plates for locking the plates against rotation when a selected tool is in working position.

LOUIS B. BROWN.
